[57] CLAIM

The ornamental design for a garment hanger, as shown.

DESCRIPTION

FIG. 1 is a front elevational view of a garment hanger showing my new design, the rear being a mirror image thereof;

FIG. 2 is a top plan view thereof;

FIG. 3 is a bottom plan view thereof;

FIG. 4 is a side elevational view taken from the right of FIG. 1; the side opposite being substantially a mirror image thereof.

FIG. 1

FIG. 4
